Primary Examiner — Patricia A Palasik*(74) Attorney, Agent, or Firm* — Kim IP Law Group PLLC(57) **CLAIM**

The ornamental design for a non-rotating drill bit for a down-the-hole drill hammer, as shown and described.

DESCRIPTION

FIG. 1 is a perspective view of a drill bit in accordance with the new design;

FIG. 2 is a bottom view of the drill bit of FIG. 1;

FIG. 3 is a back side elevation view of the drill bit of FIG. 1;

FIG. 4 is a front side elevation view of the drill bit of FIG. 1;

FIG. 5 is a right side elevation view of the drill bit of FIG. 1; and,

FIG. 6 is a left side elevation view of the drill bit of FIG. 1. The broken lines of FIGS. 1-6 illustrate portions of the drill bit which form no part of the claimed design.
